INVENTOR

Solomon Cohen.

UNITED STATES PATENT OFFICE.

SOLOMON L. COHEN, OF NEW YORK, N. Y.

DOOR-MAT.

SPECIFICATION forming part of Letters Patent No. 378,356, dated February 21, 1888.

Application filed November 19, 1886. Serial No. 219,351. (No model.)

To all whom it may concern:

Be it known that I, SOLOMON L. COHEN, a citizen of the United States, and a resident of the city, county, and State of New York, have 5 invented a new and useful Improvement in Door-Mats, of which the following is a specification, reference being had to the accompanying drawings, forming part thereof.

This invention has reference to an improved 10 way of placing the name of a proprietor or number and street-name of his residence on a door-mat. Heretofore door-mats have had worked into the surface in weaving of same the number and street-name of the residence to 15 which it belonged or the name of its proprietor. It, however, was expensive, and much time elapsed before the mat could be delivered after it was ordered. By my improvement I attach a device to the mat, on which device is 20 placed the number of the residence or the name of the proprietor, or both.

It consists in a ring having a flat or beveled surface, on which is to be placed such number or name. To this ring is connected a staple 25 for attaching it to the mat. Through the ring is placed the usual chain for securing the mat to the doorway.

In the drawings, Figure 1 is a front view of a mat to which my improvement is applied. 30 Fig. 2 is a longitudinal vertical section thereof taken through the line $x-x$ of Fig. 1.

a is the body of the mat.

b is a ring of metal containing a flat or suitable surface thereon for the purpose of engraving 35 the number and street-name of a residence or the name of a proprietor, or both. To this ring is attached a bifurcated staple, *c*, at its eye *d*. This staple has metal washers—one, *e*, at the top, the other, *f*, at the bottom, the mat 40 being contained between the two by reason of the staple passing through the body of such mat. The lower end of the staple can be hammered over or riveted in a secure manner, so as to prevent its detachment from the mat. 45 Through the ring *b* passes a chain for securing the mat to the doorway.

I am aware that heretofore rings have been attached to door-mats, by which they were secured, and, as hereinbefore remarked, that the

inscription of the name of the owner, &c., has 50 been worked into the body of the mat. By my invention I dispense with the latter costly means of inscribing the mat, and by modifying the construction of the ring and arranging it to lie upon the upper surface of the mat I accomplish 55 in a very inexpensive manner the double purpose of furnishing means for securing the mat in place and of prominently exposing the inscription of ownership. It is also to be observed that while the ring is attached 60 to the mat by the washers and staple so securely as to prevent theft, it may, when desired, be readily removed by proper tools, and the ring be thus applied in succession to and perform its double duty with a great many 65 mats, thus still further decreasing the aggregate expense heretofore attendant upon the accomplishment of the two purposes.

The arrangement of the ring so as to lie upon the upper surface of the mat has the further 70 advantage of securing the ring from damage by the movement of the mat toward the wall or other rigid body.

I claim—

1. The combination, with a door-mat, of a 75 ring having a flat face for a name or inscription and an eye therefor fixed to the mat upon the face and at a distance from the edge thereof and receiving the ring, whereby said ring is caused to lie securely upon the upper surface 80 of the mat, the inscription of ownership is prominently exposed, and means are provided for securing the mat to a doorway, all substantially as set forth.

2. The combination, with a door-mat, *a*, of 85 the ring *b*, having upon its face a flat surface for inscription of ownership, the bifurcated staple *c*, having an eye, *d*, receiving the ring, and the washers *e f* on the upper and under side of the mat, the staple passing through the washers and clamping the mat between them, and securing the ring to the upper surface thereof, so that the inscription shall be prominently exposed, for the purpose set forth.

SOLOMON L. COHEN.
